FIG. 1

FIG. 2

INVENTOR

Henry P. Coulter,
By Sam. C. Crampton,
His atty.

UNITED STATES PATENT OFFICE.

HENRY P. COULTER, OF TOLEDO, OHIO.

DUST AND WIND GUARD FOR CAR-WINDOWS.

1,267,381.

Specification of Letters Patent. Patented May 28, 1918.

Application filed October 22, 1917. Serial No. 197,891.

To all whom it may concern:

Be it known that I, HENRY P. COULTER, a citizen of the United States, and resident of Toledo, in the county of Lucas and State 5 of Ohio, have invented a certain new and useful Dust and Wind Guard for Car-Windows; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to railway appliances, and particularly to a dust and wind-guard for use in connection with the windows of railway cars.

20 The object of my invention is the provision of an improved device of the character described, which is permanently attached to a car, can be easily and quickly placed in operative or usable position, and, when not in use, may be disposed out of view within 25 the window-casing and adjacent car wall.

25 The invention is fully described in the following specification, and while, in its broader aspect, it is capable of embodiment in numerous forms, a preferred embodiment 30 thereof is illustrated in the accompanying drawings, in which—

35 Figure 1 is a perspective view of a portion of a railway passenger coach embodying the invention, with a part broken away, and Fig. 2 is a similar enlarged view of a portion of a coach with the invention in usable 40 position and parts broken away.

Referring to the drawings, 1 designates a 45 railway passenger coach having the window-casings 2 and the window-sashes 3 vertically movable therein to open and closed position, as is well understood in the art.

50 The window-sill of each casing 2 is provided in vertical register with the respective sash 3 with a slot 4, which extends longitudinally of the sill from one end thereof and opens communication with the space between the inner and outer walls of the coach-side. A pivot-rod 5 is fixed at its upper end 55 to the lower edge portion of each window-sash 3 adjacent to one side edge thereof for raising and lowering movements therewith and extends therefrom down through the sill-slot 4 and into the wall space of the coach, being preferably guided for movement at its lower end portion by a guide 6

provided in the wall space. Each rod 5 also extends through a guide 7 provided in the inner end portion of the sill-slot 4.

A dust and wind-guard plate 8 is pivoted 60 at one edge to each rod 5 and is adapted to have raising and lowering movements through the associated sill-slot 4. When a guard-plate has been lowered into a slot 4 its lower end portion extends down into the 65 registering wall space so that the guard-plate is in inoperative or out-of-view position. The lowering movements of the guard-plate are limited, in the present instance, by the hinge-lugs thereof, which receive the rod 5, coacting with the respective rod-guides 6 and 7. The upper edge of each guard-plate is preferably provided with an upwardly projecting hand-hold portion 9, which, when the guard-plate is in lowered 70 position, projects above the top of the window-sill and enters a registering bottom recess 10 in the window-sash.

When the window-sash 3 has been raised a height which is slightly greater than the 80 length of the associated guard-plate 8 the guard-plate can then be raised from within the wall chamber and sill-slot 4 and turned outward to operative position at the adjacent side of the window-casing. The guard-plate is retained in such operative position by a catch-finger 11, which projects from the lower portion of the window-casing and has a top-notch for receiving the lower edge of the guard-plate. When a guard-plate has 90 been placed in holding engagement with the catch 11 the associated window-sash is then lowered into engagement with the top of the plate to coöperate with the catch-finger to retain the plate in operative position. 95

It is evident with my invention that when a guard-plate is disposed in inoperative position within the wall chamber and the associated window-sash is in closed position that the guard-plate is entirely out of view inasmuch as the top edge of the plate and the sill-slot 4 are entirely covered by the sash. It is also evident with my invention that a guard-plate is always at hand for use in connection with a window and the plate is not 100 liable to become lost or misplaced.

I wish it understood that my invention is not limited to any specific construction, arrangement or form of the parts, as it is capable of numerous modifications without 110 departing from the spirit of the claims.

Having thus described my invention, what

I claim as new, and desire to secure by Letters Patent, is—

1. In combination, a window-casing having a slot in its sill portion, a sash vertically movable in said casing, a pivot-rod fixed to the bottom portion of said sash for movement therewith and extending down through said slot, a guard-plate pivotally carried by said rod and adapted to be disposed in inoperative position in said slot and, when the sash has been raised, to be taken from said slot and swung outward on said pivot-rod to operative position relative to the casing.

2. In combination, a wall having a chamber therein, a window-casing having a slot disposed longitudinally in its sill portion and in communication with said chamber, a

sash vertically movable in said casing, a rod projecting downward from the lower portion of said sash through said slot and into said chamber and movable with the sash, a guard-plate mounted on said rod for pivotal and longitudinal sliding movements relative thereto, said plate being movable into inoperative position in said slot and chamber and, after a raising of the sash, adapted to be raised within the casing and then swung outward to operative position, and means for retaining the guard-plate in operative outwardly swung position.

In testimony whereof, I have hereunto signed my name to this specification.

HENRY P. COULTER.
